UNITED STATES PATENT OFFICE.

GEORGE A. DEAN AND SAMUEL E. HALL, OF WAYLAND, TEXAS.

GRAIN-FENDER.

No. 857,874.

Specification of Letters Patent.

Patented June 25, 1907.

Application filed March 27, 1907. Serial No. 364,888.

To all whom it may concern:

Be it known that we, GEORGE A. DEAN and SAMUEL E. HALL, citizens of the United States, residing at Wayland, in the county of 5 Stephens and State of Texas, have invented a new and useful Grain-Fender, of which the following is a specification.

This invention has relation to grain fenders adapted to be applied to the divider and 10 tail boards of a grain table and it consists in the novel construction and arrangements of its parts as hereinafter shown and described.

The object of the invention is to provide a grain table attachment of the character indicated which is adapted to shunt or throw the grain as it is cut upon the grain table and away from the grain that is left standing.

The attachment consists primarily of a member which is attached to the grain divider and which projects in advance of the same. The said member is provided with an 20 upwardly and rearwardly inclined portion. A tail board is pivoted to the divider. A standard or standards are mounted upon the 25 tail board and a bar is pivoted at an intermediate point to the said standard or standards and at its forward end to a link which in turn is pivoted to the first said member.

In the accompanying drawing:—Figure 1 30 is a top plan view of the fender, and Fig. 2 is a side elevation of the same.

The grain table 1 is provided with the usual divider board 2 to which is attached, by means of a pivot, the tail board 3. The said 35 parts are arranged and constructed as usually found in harvesters or reapers. The tail board 3 is disposed at an angle to the end of the grain table 1 and is located above the same; consequently, the rear portion of the 40 board 3 is supported by contact with the end of the grain table, but the board 3 may swing on its pivot in an arc above the table 1. The fender attachment consists of the member 4 which is mounted upon the outer side of the 45 divider 2. Said member consists of the lower substantially horizontal portion 5 which projects at its forward end beyond the point of the divider 2 and merges into the upwardly and rearwardly inclined portion 6. 50 The member 4 is preferably made from sheet metal and has its flat sides vertically disposed in order to pass readily through the grain and to throw the cut grain laterally. The V-shaped standard 7 is mounted upon

the outer side of the tail board 3. The apex 55 of the standard 7 is uppermost. The bar 8 is pivoted at an intermediate point to the apex of the standard 7 and at its forward end to a link 9, the lower end of which is pivoted to the lower portion 5 of the member 4. The 60 link 9 is not equal in length to the vertical height of the standard 7 consequently the forward end of the bar 8 is downwardly inclined. The standard 7, bar 8 and link 9 are also preferably made from sheet metal and 65 have their flat sides vertically disposed in order to readily penetrate the grain. By reason of the pivotal connections between the bar 8, standard 7, and the bar 8 and link 9, the tail board 3 may swing upon its pivotal 70 connection with the divider 2 and at the same time the bar 8 is connected with but not attached directly to the said divider and tail board.

From the foregoing description it is obvious that as the grain is cut and passed upon the grain table the fender will separate the cut grain from the grain left standing and throw the cut grain laterally upon the table. Thus, there is no possibility of the grain falling laterally from the table over the end and tail boards.

Having described our invention what we claim as new and desire to secure by Letters-Patent is:—

1. In combination with a grain table having a divider board and tail board pivoted to the divider board, a fender comprising a pointed member attached to the divider board, a standard erected upon the tail board, a bar pivoted to said standard and a link pivotally connecting the forward end of the bar to said member.

2. In combination with a grain table having a divider board and a tail board pivoted 95 to the divider board, a fender comprising a member attached to the divider board and having an upwardly and rearwardly inclined portion, a standard erected upon the tail board, a bar pivoted to the said standard and 100 a link pivotally connecting the forward end of the bar with said member, said link being shorter than the length of the standard.

3. In combination with a grain table having a divider board and a tail board pivoted 105 to the divider board, a fender comprising a pointed member attached to the divider board, a standard erected upon the tail board,

a bar pivoted to said standard, a link pivotally connecting the forward end of the bar with said member, the said member, the standard, the bar and the link being made
5 from sheet metal, the plane surfaces of which are substantially vertically disposed.
In testimony that we claim the foregoing

as our own, we have hereto affixed our signatures in the presence of two witnesses.

GEORGE A. DEAN.
SAMUEL E. HALL.
